CARBON SHIELD

Louis J. Miller, Chicago, Ill., assignor to United
Autographic Register Co., Chicago, Ill., a cor-
poration of Illinois

Application March 30, 1931. Serial No. 526,520

4 Claims. (Cl. 197—126)

This invention relates particularly to duplicating machines adapted to the purpose of filling in forms on continuous-form stationery.

The invention is more particularly adapted to a machine comprising a bed equipped with a plate-form platen, and a typewriter movably mounted on the bed and adapted to the purpose of typing in forms.

The primary object is to provide an improved means for shielding certain areas of some of the manifold slips so that those portions of the writing will not be transferred to underlying slips.

In accordance with the present invention a thin bar is supported at the edge of the platen and carries a sheet of shielding material of a desired shape which extends over the platen with the carbon-strips.

The invention is illustrated in a preferred embodiment in the accompanying drawings, in which—

Figure 1 is a side elevational view of a machine embodying the invention; Fig. 2, a broken transverse vertical sectional view taken as indicated at line 2 of Fig. 1; Fig. 3, a broken plan view of the machine; Fig. 4, a perspective view of the sheet, supporting bar and clamp; Fig. 5, a transverse sectional view of the device taken as indicated at line 5 of Fig. 4; and Fig. 6, an enlarged broken side elevational view showing one of the supporting studs taken as indicated at line 6 of Fig. 2.

Referring to the drawings, A designates a main frame comprising a standard A' and a bed A²; B, a platen mounted in the front portion of said bed; C, a typewriting device movably mounted on the rails which constitute the bed A² of the machine; D, a carbon-supply device carried by the bed A²; E, a carbon-shield device carried by the supporting brackets of the carbon-supply device D; and F, a stationery supply-roll.

The front bracket 10 and the rear bracket 11 of the carbon-supply device are provided with stud-supporting arms 12 and 13, respectively, which are rigidly connected to the brackets by means of screws 14. Studs 15 are fixedly mounted on the supporting arms and disposed substantially perpendicular to the plane of the carbon-strips extending towards the platen. The upper portion 15^a of the stud 15 is of smaller diameter than the base portion and provides a shoulder near the central portion. A thin flat sheet-supporting bar 16 is provided with holes 17 which are adapted to slip freely

over the upper portions 15^a of the studs and are guided thereby. A U-shaped clamping member 18 is connected to the bar 16 by means of a pivot 19. A sheet 20, which is fastened to the bar by means of the clamping member, 60 is of a thin flexible material, such as cellophane, cloth, cardboard, or the like. Preferably, the sheet is rather stiff, so that it will not be displaced or wrinkled when fresh stationery is drawn over the platen and support from one 65 side of the platen will be sufficient. The sheet may be cut out so that only certain areas will be shielded, and different sheets may be used to meet different requirements.

In some cases it is desirable to block out 70 similar areas of several slips which underlie the carbon shield. In that case, a sheet of hard cold rolled steel .015 of an inch in thickness may be used. For ordinary use, however, where only one sheet is to be blocked out and 75 the type is to print through the shield to the underlying slips, cellophane of .0015 thickness has been found very satisfactory.

By reference to Figs. 2 and 3, it will be seen that the sheet-supporting bar may be inserted 80 between any of the carbon-strips so as to shield as many copies as desired. The bar, being rather light and freely mounted on the studs, will be supported primarily by the carbon strips and will float between the strips and carbons. When 85 it is used in connection with carbon-strips from a supply-roll, the bar will assume lower positions on the studs as the expending of carbon reduces the diameter of the roll.

In the illustration given, a single carbon-shield is shown attached to the left-hand side 90 of the machine, but obviously shields may be attached to either or both sides of the machine, and several shields may be carried by one set of studs, if desired.

The foregoing detailed description has been given for clearness of understanding only and no unnecessary limitations should be understood therefrom, but the appended claims should be construed as broadly as permissible in view of 100 the prior art.

What I regard as new, and desire to secure by Letters Patent, is:

1. In combination: a frame comprising spaced horizontal arms and an intervening flat platen 105 over which paper-webs may be drawn from the rear; means for supporting carbon-strips interleaved with and extending over the platen transversely of said paper-webs; and an upwardly slidable impression-preventing carbon shield 110

mounted outside of said frame near one lateral edge of the paper webs and extending with the carbon-strips over a portion of the platen.

2. In a machine of the character set forth: a frame comprising spaced arms and an intervening flat platen; a pair of outwardly extending brackets mounted on one of said arms and adapted to support a carbon-supply device from which a carbon-strip may extend over said platen; carbon shield supporting members mounted on said brackets; and an impression-preventing carbon shield loosely connected to said supporting members and slidably upwardly thereon.

3. Mechanism of the character set forth in claim 2, in which the carbon shield supporting members comprise upwardly extending studs, and in which the carbon shield is provided with a supporting bar having openings adapted to

movably engage said studs and float between said carbon strips.

4. In a machine of the character set forth: a frame having spaced arms and an intervening flat platen; a pair of outwardly extending brackets mounted on one of said arms and adapted to support a carbon-supply roll from which carbon-strips may extend over said platen; upwardly extending studs mounted on said brackets near the marginal edges of said carbon-strips; and a carbon shield device interposed between said carbon-strips and extending over a portion of said platen, said device comprising a supporting bar having holes slidably engaging said studs, and an impression-preventing sheet fastened onto said supporting bar.
